(57) **CLAIM**

The ornamental design for a flight simulator cockpit, as shown and described.

DESCRIPTION

FIG. 1 is an upper front perspective view of a flight simulator cockpit showing my new design;

FIG. 2 is an upper rear perspective view thereof;

FIG. 3 is a right view thereof;

FIG. 4 is a left view thereof;

FIG. 5 is a top view thereof;

FIG. 6 is a bottom view thereof;

FIG. 7 is a rear view thereof;

FIG. 8 is a front view thereof;

FIG. 9 is a lower front perspective view; and,

FIG. 10 is a lower rear perspective view.

The broken lines illustrate portions of the flight simulator cockpit that form no part of the claimed design.
